ROBERT G. REDMANN, OF BRISTOL, CONNECTICUT, ASSIGNOR TO THE SESSIONS
FOUNDRY COMPANY, OF BRISTOL, CONNECTICUT, A CORPORATION

MANHOLE COVER

Application filed July 8, 1929. Serial No. 376,821.

My invention relates to improvements in manhole covers, of the form involving the use of a casing or boxing that is set in the ground or roadway and a cover for closing the upper end thereof, and the object of my improvement is to produce a boxing and cover combination in which the seat in the boxing is provided in an inwardly projecting flange that is interrupted at intervals by cross-slots for admitting the ends of a locking structure on the cover, which ends serve as locking lugs in engagement with the under face of said flange, and in which the flange sections intermediate the cross-slots are of helical form, after the manner of a screw-thread for effecting the locking responsive to turning of the cover.

In the accompanying drawings:—

Figure 1 is a side elevation of a manhole boxing and cover structure embodying my invention, a wrench being shown in engagement with the cover.

Fig. 2 is a plan view of the same.

Fig. 3 is a sectional view on an enlarged scale on the line 3—3 of Fig. 2.

Fig. 4 is a bottom view of the cover.

Fig. 5 is a bottom view of the boxing.

Fig. 6 is a fragmentary sectional view through one of the locking joints.

Fig. 7 is another fragmentary view, part in section, showing from the inside a portion of one of the seat supporting ribs or flange structures and one of the locking lugs.

My improved manhole cover 10 is used in combination with a base member or ring 11 that terminates at the upper end in the form of a rim 12 that is set flush with the roadway. The cover 10 fits within said rim 12, with the top face also flush with the roadway, there being just inside the rim 12 a depressed seat 14 for the edge portion 15 of the cover 10. The seat 14 is the upper face of a flange 18.

The locking of the cover is effected by means of a lug structure depending from the under face of the body portion 16 of the cover 10 that engages with the under face 17 of the flange 18 that supports the depressed seat 14, and which under face 17 is inclined, after the manner of a helical structure or screw-thread. Thus, responsive to turning the cover in the

right direction, which is clockwise in the present instance, and with a proper proportioning of the parts, the turning will be stopped after a forceful engagement that serves to effect a positive locking of the cover 10 and to provide a tight seating of the edge portion 15 of the cover 10 on the seat 14.

I prefer to subdivide the under face 17 of the seat supporting structure 18 by means of a plurality of cross-slots 19, as shown three in number and spaced angularly at one hundred and twenty degree intervals, and thus provide a corresponding number of under face sections 17, each of which is inclined in the manner described.

The locking lug structure that engages with the three under face sections 17 comprises a set of locking lugs 20 that are supported from the under face of the cover 10 by supporting rib structure 21 or the like so as to be in spaced relation from the cover by a separating space 22 such as to admit the seat supporting flange 18 and to operatively engage therewith in the manner described.

The base member and cover described are made of cast iron. In use they are subjected to severe conditions, involving changes in weather and temperature. Also, the parts are of relatively large diameter. The positive lock described is extremely desirable, as under present forms of construction covers become loose, rock as traffic passes thereover, resulting in objectionable noises as well as damage, in some instances being actually thrown off from the seats and away from the opening.

I find that the structure described can be relied upon for satisfactory service, particularly by the use of releasing means in the form of a relatively large wrench 23 having engaging means for connecting with the cover 10 in the form of dependent pins 24 that are spaced apart so as to engage with depressions 25 in the cover 10 that are relatively close to the periphery of the cover. The wrench 23 is a relatively large spanner wrench.

Thus even in cases where the locking contact faces may be considerably rusted they may be forcibly disengaged.

I claim as my invention:—

In manhole cover construction, an annular base having a generally cylindrical wall that is provided adjacent the upper end with an inwardly projecting flange structure that has a plain upper face that serves as a seat, said flange structure being interrupted by a plurality of cross-slots that subdivide the flange structure into a corresponding plurality of flange-sections, said slots opening into the interior open space of the base and terminating outwardly radially in spaced relation to the outer edge of the flange structure, leaving intact a seat portion at the end of the slot that merges with the adjacent seat portions on the two sides to provide a continuous uninterrupted seat face, said flange-sections being thickened generally below said seat in generally wedge-like form with the bottom face of each flange-section of helical form, a cover fitting over on top of said seat so as to substantially fully cover the same by the under face of the peripheral portion and provided on the under face with a plurality of lugs, one for each of said slots and adapted to drop through said slots and to engage when the cover is turned with the said helical bottom faces by their upper faces, said upper faces of the lugs being spaced from said under face of the peripheral portion so as to permit of initial free turning of the cover from position of registration of the lugs with the slots and as the turning is continued to pinch the flange-section in each case for effecting a positive holding of the cover.

ROBERT G. REDMANN.
